UNITED STATES PATENT OFFICE.

CHARLES N. CURRY, OF CHICAGO, ILLINOIS, ASSIGNOR OF TWENTY-FIVE ONE-HUNDREDTHS TO LATIMER GOODRICH AND TWENTY-FOUR ONE-HUNDREDTHS TO CHARLES EVANS, JR., BOTH OF CHICAGO, ILLINOIS.

GOLF-CLUB.

1,083,434.

Specification of Letters Patent.

Patented Jan. 6, 1914.

Application filed April 25, 1913. Serial No. 763,539.

To all whom it may concern:

Be it known that I, CHARLES N. CURRY, a citizen of the United States, and a resident of Chicago, in the county of Cook and State of Illinois, have invented certain new and useful Improvements in Golf-Clubs, of which the following is a full, clear, and exact specification.

As is well known to all players of the game, the main difference between the various iron clubs used, such as the putter, mid-iron, mashie and niblick, resides in the angle at which the striking surface of the blade is presented to the ball when it is struck thereby, and the object of my invention is to produce a single club, which, by adjusting the angle at which the blade stands to the shank, can be used for any one of a plurality of clubs, such as those above enumerated.

To illustrate my invention, I annex hereto a sheet of drawings, in which the same reference characters are used to designate identical parts in all the figures, of which,—
25 Figure 1 is a side elevation of a club embodying my invention, a portion of which is in central longitudinal section; Fig. 2 is an end elevation of the same; Fig. 3 is a view of the other end of the blade detached; Fig. 4 is a side elevation of the blade detached; Fig. 5 is a top plan view of the blade detached; Fig. 6 is a sectional view through the shank and blade, on the line A—A of Fig. 1; and Fig. 7 is a view similar 35 to a portion of Fig. 2, showing a modification of the means employed for holding the plunger in place.

In carrying out my invention, the customary shaft *a* is secured in the upper end 40 of the shank *b* in the customary manner. Instead of having the shank *b* integral with the blade *c*, as is the customary practice, I make them separate and provide the following connections for adjusting the angle at 45 which the blade shall stand.

The shank *b* has bored through the axis thereof a tubular passage *d* adapted to receive the plunger *e*, which is preferably spring-pressed in place by a helically-coiled 50 expanding spring *f* which is held in position by a screw-head *g* threaded into the upper end of the tubular passage *d*. As seen, the lower end of the plunger is preferably tapered slightly and is adapted to coöperate

with any one of the four apertures *h* which are formed in a segmental flange *i* on the end of the blade, which flange is concentric with a bearing *j* which extends through a bearing aperture *k* in the lower end of the shank. A screw *l* is threaded into the end 60 of the blade through the bearing *j*, and is locked in place by a set-screw *m* which is screwed into the bottom of the blade at right angles to the body of the screw *l*. It will be observed that the screw *l* coöperating with the shank serves to prevent any movement of the blade relative to the shank except the movement of rotation heretofore described. The end of the shank *b* is preferably enlarged so as to form a segmental 70 channel *n* in which the flange *i* fits snugly, and the channel *n* is of sufficient length so that the apertures *h* are covered in all adjustments of the blade to prevent dirt or other material entering the same. The end 75 of the blade *c* has a segmental channel *o* cut therein, and the side of the channel *n* in the end of the shank forms an annular flange *p* which enters the channel *o*. The coöperation of the two channels and flanges thus 80 formed on the shank and blade further serves to hold the two parts against any possible relative movement except that of rotation of the blade *c* about the bearing *j*. The blade is held in the adjusted position against 85 rotation by the plunger *e*, and to provide for the ready adjustment of the club, the plunger is provided with a pin *q* which extends through an elongated slot *r* formed in the shank, and I also provide a shield or 90 cover *s* associated with the head of the pin *q* and serving to cover the slot *r* in all positions, so as to prevent dirt getting into the passage for the plunger. As shown, I preferably make the heel of the blade *c* curved, 95 so that the club may be used with the shaft *a* at different angles to the vertical.

Instead of employing the spring *f* to hold the plunger *e* in its locking position, I may employ the L-shaped slot *r'* shown in Fig. 7, 100 and when the position of the club is to be changed, the pin *q* is turned out of the horizontal portion of the slot *r'* into the vertical portion, and then raised until the blade is released for the new adjustment, after 105 which the plunger is shoved down into the chosen aperture, and the pin *q* is then turned through the horizontal portion of the

slot r' to lock the plunger in position. I may employ both the spring f and the L-shaped slot.

While I have shown and described my invention as embodied in the form which I at present consider best adapted to carry out its purposes, it will be understood that it is capable of modifications, and that I do not desire to be limited in the interpretation of 10 the following claims except as may be necessitated by the state of the prior art.

What I claim as new, and desire to secure by Letters Patent of the United States, is:

1. In an adjustable golf-club, the combination with a shank having a latch carried thereby sliding along the axis of the shaft and having its lower end tapered in a conical form, of a blade pivotally mounted in said shank and having a plurality of flaring 20 conical recesses therein into any one of which the tapered end of the latch may extend and fit snugly to determine the angle of the blade relative to the shank, and means to hold the latch in the recess.
2. In an adjustable golf-club, the combination with a shank, of a sliding plunger therein extending along the axis of the shank, an L-shaped slot in the shank, a pin extending through said slot and connected to 30 the plunger, by which the latter may be raised or rotated on its axis as far as the slot will permit, and a blade pivotally mounted in said shank and having a plurality of recesses therein with any one of 35 which the plunger may coöperate to determine the angle of the blade relative to the shank.
3. In an adjustable golf-club, the combination with a shank having a bearing aperture set at an angle to the axis of the shaft

and having a segmental channel therein concentric with the bearing aperture, of a blade having a bearing in said aperture, and a segmental flange having recesses therein coöoperating with the channel in 45 the shank, a plunger in the shank having its end adapted to enter any one of the recesses, and means for holding the plunger in the recess.

4. In an adjustable golf-club, the combination with a shank having a bearing aperture set at an angle to the axis of the shaft and having a segmental channel therein concentric with the bearing aperture, of a blade having a bearing in said aperture, and a segmental flange having recesses therein 55 coöoperating with the channel in the shank, a plunger in the shank having its end adapted to enter any one of the recesses, and means for holding the plunger in the recess, 60 the segmental channel being long enough to cover the recesses in any position of adjustment of the shank.

5. In an adjustable golf-club, the combination with a shank having a bearing aperture set at an angle to the axis of the shaft and having a segmental channel therein concentric with the bearing aperture, of a blade having a bearing in said aperture and a segmental flange coöoperating with the channel 70 in the shank, and means interposed between the shank and blade to lock the same in different relative positions.

In witness whereof I have hereunto set my hand and affixed my seal, this twenty- 75 second day of April, A. D. 1913.

CHARLES N. CURRY. [L. s.]
